UNITED STATES PATENT OFFICE.

JOSEPH J. FERRARI, OF SYRACUSE, NEW YORK.

ADJUSTABLE ERASER.

1,136,592.

Specification of Letters Patent. Patented Apr. 20, 1915.

Application filed December 13, 1913. Serial No. 806,357.

To all whom it may concern:

Be it known that I, JOSEPH J. FERRARI, a citizen of the United States, residing at Syracuse, in the county of Onondaga and 5 State of New York, have invented certain new and useful Improvements in Adjustable Erasers, of which the following is a specification.

This invention relates to improvements in 10 erasers, and has for its object to provide a novel, simple and inexpensive eraser especially adapted for use in connection with typewriters.

A further object is to provide a novel 15 and simple holder for the eraser.

A further object is to provide means for adjusting the eraser relatively to the holder, for exposing one end of it while in use, the said means capable of concealing the eraser 20 within the hollow holder for keeping it clean while not in use. And a further object is to provide means for readily and quickly applying, removing and replacing the eraser.

The various features and parts of the 25 invention will be understood from the detailed description which follows, and by reference to the accompanying drawing, which forms a part of the specification, and in 30 which—

Figure 1 is an elevational view; showing the complete device ready for use. Fig. 2 is a central longitudinal section, taken on line 2—2 of Fig. 1; showing the construction and arrangement of the parts of the device; also showing means for adjusting and holding the eraser in any desired position. Fig. 3 is a view; showing the method of applying, and removing the eraser from 40 the holder. Fig. 4 is a view; showing modified means for securing the detachable cap to the body of the holder. Fig. 5 is a view; partially in elevation and partially in section; showing a modified form of eraser.

In the drawing, 2 represents the hollow tube-like body of the holder, which may be made out of any suitable metal, or celluloid. One end 3, of the body is closed, while the opposite end 4 is open. In the preferred 50 form of the device, the end 4 is provided with external threads, to receive a detachable tubular cap 5. One end of the cap is slightly expanded at 6, and this portion is internally threaded for screwing on to the body. The opposite end of the cap is pref-

erably contracted to provide a dull point 7, having a rectangular or square opening through which one end of the eraser 8 projects when in use.

The eraser 8 may consist of any material 80 or substance suitable for erasing or removing ink or lead pencil marks from paper. But I prefer to employ for this purpose spun glass, comprising a number of hair-like parts, which when collected, as shown, 85 in Figs. 2, 3, and 4 resemble a brush.

9 represents a hollow cup-like base or head, into which one end of the brush 8 is inserted. After the brush eraser 8 is inserted in the head 9, the metal comprising 70 the open end is pressed or spun at 10 for contracting the mouth and thereby tightly gripping and holding the eraser in place. The closed end of the base or head 9 is provided with a hook 11 secured at its heel to 75 one edge of the head and having its free or toe portion projecting transversely of said head. The eraser 8 is adjustably held in the holder by means of a reciprocating skeleton plunger or feeder 12, which consists of 80 a metal bar or strip 13, which is bent U-shaped at one end to provide a loop or stirrup 14 which is engaged by the toe of the hook 11 of the eraser head 9. The opposite end of the bar 12 is fitted with a screw stud 85 15 which projects through and plays in a relatively long slot 16 formed longitudinally in the body 2. And 17 represents a thumb-nut which is screwed on to the outer end of the screw 15, by means of which the plunger and eraser are moved back and forth in the casing 2. The breadth of the loop 14 is preferably the same as the inner diameter of the tube 2, which permits the plunger to reciprocate, but does not allow any lateral 90 play which might disturb the eraser. The nut 17 when screwed down tight against the outer surface of the shell 2, holds the plunger and eraser in the desired position. The slot 16 of the body 2 is of sufficient length 95 to allow the eraser to be fed through the cap 5, until it wears away. When the plunger is moved away from the cap the full distance allowed by the slot 16, the eraser is entirely disposed within the holder and thus 100 105 may be kept clean.

Fig. 3 shows the plunger 12 operated to its fullest extent for ejecting, as well as permitting the installing of a new eraser, in which the loop 14 projects slightly beyond 110

the open end 4 of the cylinder 2 to receive the hook 11. After the eraser is attached to the plunger, these parts should be drawn into the cylinder 2 the full distance, for allowing the cap 5 to be screwed on to the tube without distorting the brush 8. When the parts are all assembled, as described, the user should slide the plunger in the opposite direction for bringing the free end of the eraser to the working position, slightly extended beyond the free end of the cap 5, as shown at 8' in Figs. 1, 2, 4 and 5. As the eraser wears away, the nut 17 may be loosened and the brush moved in the direction for presenting a new wearing point.

In Fig. 4 I have shown the well-known bayonet catch for securing the cap 5' to the body 2, which consists of forming an angular internal groove 18 in the expanded end 6' of the cap, which engages a pin 19 carried by the body 2. This form of catch is effective, and the coupling may be quickly made.

In Fig. 5 I have shown an eraser 20, which consists of an elongated stick of rubber, which may be made square or rectangular in cross-section, to conform to the opening in the cap. The inner end of the eraser 20 may be secured in the socket of the head 9, in practically the same manner as the spun glass brush 8, and the operation of the rubber

eraser is the same as described for the glass eraser.

Having thus described my invention, what I claim as new and desire to secure by Letters Patent, is—

In a device of the character described an implement, a tubular holder therefor having a slotted side, and means for adjusting the implement in the holder comprising a metal strip member slidable longitudinally of the holder with its shank portion adjacent to and parallel with said slotted side and bent at its lower end to constitute a stirrup, the terminal portion of which is parallel to the opposite side of the holder, adjusting means for said member engaging the slotted side and adjacent shank portion, said adjusting means permitting the member to project beyond the lower end of the holder to present an open eye extending through said member between its shank and terminal portions, and a hook carried by the implement secured at its heel portion thereto and free at its toe portion to pass through said eye and be suspended thereby, substantially as described.

In testimony whereof I affix my signature in presence of two witnesses.

JOSEPH J. FERRARI.
